UNITED STATES PATENT OFFICE.

GEORGE R. JARMAN, OF BALTIMORE, MARYLAND, ASSIGNOR TO GEORGE W. S. LOUCKS AND WILLIAM H. WHEELER, BOTH OF YORK, PA.

ICE-MACHINE.

SPECIFICATION forming part of Letters Patent No. 349,798, dated September 28, 1886.

Application filed March 19, 1886. Serial No. 195,816. (No model.)

To all whom it may concern:

Be it known that I, GEORGE R. JARMAN, a citizen of the United States, residing at Baltimore, State of Maryland, have invented certain new and useful Improvements in Ice-Machines, of which the following is a full, clear, and exact description.

This invention relates to certain features in the construction and operation of that class of ice-making machines in which the process is carried on by the expansion of a refrigerating gas or fluid conducted in pipes in contact with the water to be frozen.

The invention consists in means for securing the equable distribution of the refrigerating medium through the conducting pipes or coils, and also in means for securing a similar exhaustion of the spent refrigerant from the pipes and its return to the condensing mechanism for reuse.

In the accompanying drawings, in the several figures of which like parts are similarly designated, Figure 1 is a plan view of a freezing-tank equipped with my invention. Fig. 2 is a vertical longitudinal section in the plane of line *x x*, Fig. 1. Fig. 3 is a vertical cross-section in the plane of line *y y*, Fig. 1; and Fig. 4 is a cross-section on line *z z*, Fig. 2, of the distributor.

The letter *A* indicates a refrigerating-tank of proper dimensions and approved construction. This tank is supplied with a series of suitable coils or "zigzags" of pipes, *a*, set vertically therein at proper distances apart.

b is the refrigerant-distributer, into which the refrigerant is introduced through a pipe, *c*. This distributer is arranged at or near the top of the tank, and is by preference a rectangular box, preferably cast in one piece, with an internal prismatic partition, *d*, extending from the vertical end next the inlet nearly to the opposite end, where its end *e* is truncated or beveled or inclined downward to the bottom of the box. The sides *f f* of this partition are inclined at about the angle of the end *e* from the apical ridge *g* (which is about in the longitudinal center of the box) to about the bottom of the box, and said partition is nearly equal in height to the height of the box. At the base—front and sides—of the partition *d*

a series of holes or openings, *h*, are made in the distributer, said openings being equal in number to the number of coils to be used in the tank. A series of small pipes, *i*, are secured by suitable gas-tight joints in these holes, 55 and thence lead into and are secured by gas-tight joints, one to each coil of the series of coils, the preferred order of such connection with respect to the distributer being indicated in the drawings, Fig. 1—that is to say, the 60 pipes nearest the inlet to the distributer being connected to the outermost coils, and those most remote being secured to the innermost coils.

In order to utilize to the best advantage the 65 expansion of the refrigerant, I make the distributer comparatively small, and its education-pipes of about half the diameter of the coils, so that the refrigerant will expand very little until it gets into the coils, the proportions 70 shown in Fig. 1 being substantially correct in this respect. The partition in the distributer serves to direct and disperse the incoming refrigerant in equal and uniform quantities to each of the several education-pipes—a thing 75 heretofore impossible, so far as my knowledge of ice machinery extends. I deem this feature of my invention of prime importance in the economy of refrigerant and its fullest utilization.

The receiver *j* for the spent refrigerant is arranged at or near the bottom of the end of the tank opposite the distributer, and receives into its lower or bottom portion the outlets of the several coils. This receiver may be made 85 of boiler-plate, castings, or other suitable strong material. The sides, ends, and top of this receiver are so proportioned that the suction pipe *k* will be equidistant, or substantially so, from each of the several inlets from the 90 coils. This may be accomplished by giving a sharp pitch to the top on opposite sides of a middle point, and making the ends lower than the middle, with the suction-pipe located at such middle point. In this way the suction is 95 equal and uniform on all the inlets, and hence each coil is exhausted of its spent gas at about the same time and in the same quantity.

The suction-pipe is connected to the receiver by a gas-tight joint—such, for example, as the 100

common packed gland shown. By this means of equable distribution and exhaustion of the refrigerant, all parts of the tank are under the same temperature, and may be kept so with a degree of uniformity and certainty hitherto unattainable, so far as I am aware, and hence the formation of ice progresses uniformly throughout the tank.

What I claim is—

- 15 1. An ice-machine provided with a distributer for the refrigerant, into which the refrigerant is received, and thence let uniformly and equally into each and every of the several coils, substantially as described.
- 15 2. A refrigerant-distributer for ice-machines, consisting of a gas-tight box having a prismatic partition extending its length and nearly its height, and having its sides and one end slanting toward the outlets, substantially as described.
- 20 3. A refrigerant-distributer for ice-machines, consisting of a box and prismatic partition therein, cast in one piece, substantially as described.
- 25 4. The combination of the distributer, a series of coils, and connections between the distributer and coils of such dimensions as to practically prevent the expansion of the refrigerant until it reaches the coils, substantially as described.

5. In an ice-machine, a receiver for the spent refrigerant, consisting of a gas-tight vessel having its suction-pipe arranged substantially equidistant from the several inlets from the coils into the said receiver, substantially as described. 35

6. The combination of a distributer constructed to insure an equable and uniform distribution of refrigerant to the coils, the coils connected thereto, and a receiver for the spent refrigerant having a suction-pipe arranged substantially equidistant from the inlets of said coils into said receiver, substantially as described. 40

7. The combination of a distributer having 45 a prismatic partition, a series of coils connected with it, and a receiver into which said coils open, and having a suction-pipe substantially equidistant from the entrances of said several coils into the receiver, substantially as described. 50

In testimony whereof I have hereunto set my hand this 17th day of March, A. D. 1886.

GEORGE R. JARMAN.
